RAYMOND G. MOORE AND ARTHUR CLAUD-MANTLE, OF BRIDGEPORT, CONNECTICUT,
ASSIGNORS TO THE BASSICK COMPANY, OF BRIDGEPORT, CONNECTICUT, A CORPOR-
ATION OF CONNECTICUT

CABINET LATCH

Application filed May 23, 1928. Serial No. 279,864.

The present invention relates to an improved cabinet latch, particularly of the type adapted for use on the doors of medicine cabinets, book-cases, and the like, and has for an object to provide a simple, compact and inexpensive latch of this character adapted to effect a tight closure, and which may be operated to open the door by turning the knob in either direction. A further object is to provide a latch which may be operated with equal facility, whether applied to the right or left of the door, and which may be attached as a unit, merely by boring a hole in the door. Another object is to provide a latch which may be economically manufactured from sheet metal stampings, and permanently assembled by a single securing operation.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a horizontal sectional view of a portion of a door and door casing, showing the latch, according to the present invention, in side elevation.

Fig. 2 is a longitudinal sectional view of the latch.

Fig. 3 is a rear elevation of the latch in its normal projected position.

Fig. 4 is a similar view showing the same in retracted relation.

Fig. 5 is a perspective view of the several parts of the latch in separated relation.

Similar reference characters indicate corresponding parts throughout the several figures of the drawings.

Referring to the drawings, the latch, according to the present embodiment of the invention, comprises a base plate 10 formed from flat sheet metal and having an aperture 11 near its forward edge, in which the upper end of a tubular guide member 12 is secured by peening over, as at 13, the plate 10 adapted to be secured to the inner side of the door 14 by screws 15 engaged through holes 16 in the plate, said member 12 being engaged in a drilled passage 17 in the door, with

its forward edge substantially flush with the outer surface of the door. The base plate is provided at its forward edge with an upwardly bent relatively wide flange 18, having a wide T-shaped cut-out 19 there-in providing a latch bolt guide, the base of this recess being slightly spaced and in parallel relation to the surface of the plate, and the contracted portion of the recess providing retaining lugs 20 and 21 at each side adapted to engage and retain the latch bolt.

The rearward portion of the base plate is of reduced width, and is provided with an upwardly bent flange 22 having a slot 23 there-in adapted to receive and guide the tail portion of the latch bolt, as will presently more fully appear, and between said flange 22 and the aperture 11 there is provided a slot 24 within which a portion of the latch bolt spring is adapted to project.

The latch bolt is formed from flat sheet metal and comprises a forward relatively wide portion 25 adapted to have sliding engagement in the cut-out 19, a relatively long narrow tail portion 26 adapted to have sliding engagement in the slot 23, and an intermediate portion 27, wider than the tail portion to provide abutment shoulders for the spring, and slightly narrower than the space between the lugs 20 and 21, to permit easy assembly by first engaging the portion 27 between said lugs, and thereupon sliding the bolt inwardly to engage the forward portion 25 beneath said lugs and the tail portion in the slot 23. The intermediate portion 27 is provided along each of its longitudinal edges and in rearwardly spaced relation to the forward portion 25 with outwardly extending lug projections 28 and 29, bent upwardly, as at 30 and 31, to provide abutment means for the double-acting latch reTRACTING handle means, presently to be described. An elongated slot 32 is provided in the latch bolt through which said reTRACTING handle means extends, and which permits relative projecting and retracting movement of the latch bolt.

At its forward edge the latch bolt is provided with a rearwardly bent hook like finger 33 for engagement with the keeper during closing of the door.

Within the tubular guide 12 there is rotatably engaged a tubular post 34, extending at its inner end through the slot 32 of the latch bolt, and having secured thereon an oscillatory retractor plate 35 having laterally extending wings 36 and 37, adapted to respectively engage the lugs 30 and 31 of the latch bolt. The plate 35 is secured by shouldering the post, as at 36, peening 10 over the end of the post upon the upper surface of the plate, as at 38, and indenting, as at 38^a, to rigidly secure the plate against relative turning with respect to the post. The post is positioned longitudinally, and the 15 plate 35 held in spaced relation out of contact with the surface of the latch bolt, and for this purpose the outer end of the post is reduced and shouldered, as at 39, and is engaged by an inwardly bent flange 40 at the 20 forward end of the tubular guide 12, the outer end of the post being peened over, as at 41. The post is interiorly threaded as at 42, and the threaded shank 43 of the knob 44 is screwed therein, the back of the knob abutting 25 the peened over flange 41 which spaces it from the door surface.

The latch bolt coil spring 45 is engaged upon the tail portion 27, between the intermediate portion 26 and the flange 22, a portion 30 of the spring projecting into the slot 24, so that a relatively large spring may be employed, without increasing the thickness of the complete latch.

The latch keeper is formed of a single piece 35 of sheet metal having a beveled strike portion 46, adapted to be engaged by the finger 33 of the latch bolt, in closing the door, to press the latch bolt inwardly to the point where it enters behind the beveled outwardly bent wedge portion 47 of the keeper. The 40 action between the portion 47 and the spring pressed latch bolt is such that a tight closure is maintained, and any variations that may develop, due to warping of the door, and other 45 causes, will be compensated for.

Normally the latch bolt is projected by the spring, the lugs 30 and 31 bearing upon the wings 36 and 37 of the retractor plate, and maintaining the position of the handle. The 50 bolt is retracted by turning the handle either direction, one of the wings 36, 37 bearing upon its respective lug 30, 31, while the other wing swings into the open space between the lugs 20 and 21. In closing the door the latch bolt retracts through engagement with the keeper, without the necessity for turning the handle.

We have illustrated and described a preferred and satisfactory embodiment of my 60 invention, but it will be obvious that changes may be made therein, within the spirit and scope thereof, as defined in the appended claims.

Having thus described our invention, what

we claim and desire to secure by Letters Patent is:—

1. In a latch for a movable closure or the like, an attaching plate, a tubular handle guide secured to said plate and adapted to be inserted in a hole in the closure, a reciprocating latch bolt mounted on said plate having an elongated longitudinal slot, a rotary handle member engaged in said guide and extending through said slot, and an oscillatory 70 plate secured to said handle member and adapted upon movement in either direction to retract said bolt.

2. In a latch for a movable closure or the like, an attaching plate, a tubular handle 80 guide secured to said plate and adapted to be inserted in a hole in the closure, a reciprocating latch bolt mounted on said plate having an elongated slot, and transversely aligned projecting lugs at each side of said slot, a rotary handle member engaged in said guide and extending through said slot, an oscillatory plate secured to said handle member having portions engaging said lugs of the bolt and adapted upon movement of said 85 plate in either direction to retract said bolt, and spring means acting between said attaching plate and the bolt adapted to normally press the same to projected position.

3. In a latch for a movable closure or the like, an attaching plate having bolt guide flanges at its opposed front and rear ends, the front flange having relatively wide substantially T-shaped opening, the wide portion thereof constituting a bolt guide, the 95 rear flange having a relatively narrow bolt guide slot, a reciprocating latch bolt comprising a relatively wide nose portion adapted to engage the wide portion of said T-shaped opening, a relatively narrow tail 100 portion adapted to engage said narrow bolt guide slot, and an intermediate portion narrower than said nose portion and wider than said tail portion adapted during assembly 105 to engage the narrow portion of said T-shaped opening, said intermediate portion of the bolt having an elongated slot and transversely aligned projecting lugs at each side of said slot, a rotary handle member mounted on said plate and extending 110 through said slot, an oscillatory plate secured to said handle member having portions engaging said lugs of the bolt and adapted upon movement of said plate in either direction to retract said bolt, and a spring mounted on 115 said tail portion of the bolt and acting between the intermediate bolt portion and said rear flange and adapted to normally press the bolt to projected position.

4. In a latch for a movable closure or the like, an attaching plate having an opening therein, a reciprocating latch bolt mounted on said plate and having a slot, a rotary handle shaft passed through said slot and opening, an oscillatory bolt retracting member 120

secured to said handle member in superimposed relation to said bolt, and a handle member detachably secured to said handle shaft, said bolt retracting member and said handle member being larger than and incapable of passage through said slot and opening.

Signed at Bridgeport, county of Fairfield, and State of Connecticut, this 25th day of April, 1928.

RAYMOND G. MOORE.
ARTHUR CLAUD-MANTLE.
